UNITED STATES PATENT OFFICE

90,877

DESIGN FOR A PORTABLE ELECTRIC
TABLE STOVE

Harry V. Glore, Oakland, Calif.

Application July 12, 1933. Serial No. 48,694

Term of patent 14 years

To all whom it may concern:

Be it known that I, HARRY V. GLORE, a citizen of the United States, residing at Oakland, county of Alameda, State of California, have invented a new, original, and ornamental Design for a Portable Electric Table Stove, of which the following is a specification, reference being had to the accompanying drawings, forming part thereof.

Fig. 1 is a perspective view of a portable electric table stove showing my design.

Fig. 2 is a perspective view of the portable electric table stove.

Fig. 3 is a side elevation of the portable electric table stove.

Fig. 4 is a front elevation of the portable electric table stove.

I claim:

The ornamental design for a portable electric table stove substantially as shown.

HARRY V. GLORE.
